INVENTOR.

Wm. Sawyer

UNITED STATES PATENT OFFICE.

WILLIAM SAWYER, OF NEW YORK, N. Y., ASSIGNOR TO THE EASTERN ELECTRIC MANUFACTURING COMPANY, OF MIDDLETOWN, CONN.

ELECTRIC LAMP.

SPECIFICATION forming part of Letters Patent No. 227,387, dated May 11, 1880.

Application filed January 14, 1880.

To all whom it may concern:

Be it known that I, WILLIAM SAWYER, a citizen of the United States, residing at New York, in the county of New York and State of New York, have invented certain new and useful Improvements in Electric Lamps, of which the following is a full, clear, and exact description.

My invention relates to that method of electric lighting in which a pencil of carbon hermetically sealed in a glass globe charged with nitrogen gas is rendered incandescent by the passage of the electric current, and has special reference to the hermetical sealing of the opening through which the globe is filled with the nitrogen gas.

The general method of making the lamp air-tight is fully set forth in other applications filed by me, and I have therefore not included the same in the present specification, except in so far as I seal the aperture employed in filling the lamp with nitrogen. Through this aperture a metal plug, B, in the accompanying drawing, is pushed aside by a tube, through which nitrogen is forced into the lamp. The nitrogen entering this tube displaces the air, and when, finally, the lamp is charged to

a sufficient degree of purity, I withdraw the tube, still permitting the nitrogen to flow until, finally, the tube shall have passed below the interior upper surface of the cup A and the plug B is drawn down by means of the wire G. I next invert the lamp and pour melted sealing-wax around the plug B. Then I place upon the bottom of the cup A one or more soft-rubber washers, D, and, by means of screws E, I set down upon the lower cap, C, until this particular joint is air-tight. Finally, through the opening W, in which there is cut a thread suited to an ordinary gas-bracket, I pour melted bees-wax F, when the lamp is complete for use.

Having thus fully described my invention, what I claim as such, and desire to secure by Letters Patent, is—

The combination of the plug B and wire G with the cap C, having an opening, W, and the liquefiable filling material F, for the purpose of sealing the filling-joint of an electric lamp, substantially as set forth.

WM. SAWYER.
